UNITED STATES PATENT OFFICE.

JOHN P. SCHENKL, OF BOSTON, MASSACHUSETTS.

IMPROVEMENT IN PERCUSSION-FUSE FOR EXPLOSIVE SHELLS.

Specification forming part of Letters Patent No. 36,576, dated September 30, 1862.

To all whom it may concern:

Be it known that I, JOHN P. SCHENKL, a citizen of the United States of America, and a resident of Boston, in the county of Suffolk and State of Massachusetts, have made an invention of certain new and useful Improvements in Apparatus or Mechanism for Exploding the Charge of a Hollow Shot or Projectile; and I do hereby declare the said invention to be fully described in the following specification and represented in the accompanying drawings.

The apparatus to which my invention appertains is generally or technically known under the name of a "concussion-fuse for explosive projectiles." Strictly speaking, however, it has not the character of a fuse, as it operates to explode by impact a percussion-cap, in order that such may set fire to the charge of a hollow plunger.

Of the said drawings, Figure 1 is a longitudinal section, and Fig. 2 a rear end view, of such a concussion-fuse provided with my invention, the nature of which consists or may be found in the construction of the rear end of the plunger-case in such manner that it (while the fuse may be fixed on a shell) shall separate the plunger-chamber from the powder-charge of the shell, and on explosion of the charge of the plunger be broken away thereby, so as to allow the flame of such explosion to communicate with the explosive charge of the shell; also, in providing the concussion-fuse with a gunpowder or explosive charge arranged within the plunger, and so as to be fired by explosion of the percussion-powder of the cap.

In Fig. 1, A denotes the case or body of the concussion-fuse, it being provided with a screw, a, for fixing it in a shell. The said case is chambered, and contains a cylindrical slider or plunger, B, which, in order to prevent accident is fastened in position by a screw, b, which goes through the side of the case A and screws into the plunger. A metallic cap or plug, C, is screwed into the front or outer end of the case A. The plunger B has a loading-chamber, e, formed within it for the reception of a gunpowder-charge, c', which, after having been placed in the chamber, is to be kept in position by a wad or plug, d, driven into the mouth of the loading-chamber. Through the

breech of the loading-chamber a vent, d', leads and opens out of a percussion-nipple, e, affixed to such vent, and within another chamber, f, formed in the striker and around the nipple. The nipple projects a short distance out of the mouth of the chamber f, and receives a common percussion-cap, g—one formed with a flange, h, at its bottom or mouth being preferred.

In order to hold the cap on the nipple during transportation of the fuse, as well as under the impact of the striker against its inelastic abutment c' at the rear end of the chamber D of the case A, I employ an annulus, k', of leather or other proper material, and so as to fit closely to the outside surface of the percussion-cap, as well as to the inside surface of the chamber f. This annulus should be cemented into the chamber f.

The bottom rear end or breech, k, of the case A, I form with a countersunk cylindrical passage to receive the stem i of a leaden or inelastic abutment, C', which rests against the inner surface of the breech, and is formed with flanges l, m, to embrace the internal and external surfaces of the breech. This leaden abutment is bored through longitudinally and receives a plug, E, which, when the apparatus is fixed in a shell, serves to separate the powder-charge of the shell from the chamber D. It also serves under other circumstances to prevent either dirt or other extraneous matters or water from getting into the said chamber D. The purpose of the inelastic or leaden abutment is to prevent the plunger B from rebounding by the force of impact when driven backward in the chamber D at the period of explosion of the shell from a piece of ordnance. Were a rebound of the plunger to take place, the percussion-cap would be forced against the head C', and explosion of the charge of such cap might result at the commencement of flight of the shell. By making the inelastic abutment in manner as set forth—viz., with two flanges and a tubular stem—I am enabled not only to so fix it in place as to prevent it from becoming displaced under ordinary circumstances, as well as during discharge of a shell from a gun, but render it capable of receiving a plug, E, which on explosion of the powder-charge of the plunger B will be blown out of its seat, so as to enable the flame of such explosion to reach the bursting charge of the shell.

The abutment C' may be constructed solid, or without any plug-passage, as such abutment, by the impact of the shell at the termination of its flight, will be likely to be driven forward out of the breech of the body A and against the plunger, in which case the breech would be opened, and in all probability more or less of the flame of the explosion of the charge of the plunger would pass into the shell, either by going around the abutment and through the breech, or by driving the abutment through the breech and into the shell; but as there would be a probability of the abutment being strong enough to cause the plunger and the screw-head C to be driven out of the chamber D, I prefer to make the inelastic abutment with a passage through its neck for the reception of a plug, E, as described. Instead of the plug E, a simple cap of thin metal or other suitable material may be fitted on the rear part of the case A, and so as to cover the opening or passage of the abutment C. This is shown in section at m in Fig. 3.

Fig. 4 represents in longitudinal section the inelastic abutment as made with a chamber, n, having a thin bottom, o, the latter to be broken or driven out of place by the explosion of the charge of the plunger. The said Figs. 3 and 4 serve to illustrate certain modes in which I have contemplated the application of that principle or character of my improvement by

which it may be distinguished from other inventions.

Preparatory to inserting in a gun, mortar, or howitzer a shell containing my improved concussion-fuse, the plug C should be reversed in the case A, in order that the empty chamber or cavity o' may not be a bar to the explosion of the percussion-cap at the terminus of the flight of the shell.

Having described my improved concussion-fuse, what I claim is as follows:

1. The construction of the rear end of the plunger-case A in such manner that the said rear end while the fuse may be fixed in a shell shall separate the plunger-chamber e from the powder-charge of the shell, and on explosion of the charge of the plunger be broken away thereby, so as to allow the flame of such explosion to communicate with the explosive charge of the shell.

2. The concussion-fuse as made with an explosive charge arranged within its plunger, and to be fired by explosion of the cap or percussion-powder of the nipple, such being for the purpose of setting fire to the bursting-charge of the shell, as described.
